UNITED STATES PATENT OFFICE.

ROBERT N. VAN BUSKIRK, OF DETROIT, MICHIGAN, ASSIGNOR TO MORGAN & WRIGHT,
A CORPORATION OF MICHIGAN.

VULCANIZER.

Application filed March 2, 1922. Serial No. 540,415.

To all whom it may concern:

Be it known that I, ROBERT N. VAN BUSKIRK, a citizen of the United States, residing at Detroit, in the county of Wayne and 5 State of Michigan, have invented certain new and useful Improvements in Vulcanizers, of which the following is a full, clear, and exact description.

This invention relates to heaters or vulcanizers for curing rubber goods and in 10 particular, a press type of vulcanizer largely used in the manufacture of tires.

Vulcanizers as heretofore constructed have not been designed to distribute steam or 15 water, which is supplied to them at certain stages in the manufacture of tires, as uniformly as desirable. It has been the practice to provide a plurality (four or six) of inlets, these being formed by drilling or 20 tapping the shell or body portion of the vulcanizer at suitable intervals around its girth. The many piping connections that had to be made very much complicated the layout of apparatus in a press-room.

25 The present invention aims to eliminate the many piping connections heretofore employed to supply steam or water to the interior of a vulcanizer, by providing a header or channel which is adapted to be 30 supplied with steam or water through a single pipe, and which is in restricted communication throughout the entire, or a large part of, the inner circumference of the vulcanizer so that steam or water supplied to 35 the header or channel enters into the space occupied by the molds from all sides.

With the preferred embodiment of the invention in mind and without limiting intention, the invention may be said to consist 40 briefly in channeling or coring the top ring at the mouth of the shell so as to constitute it a header, this top ring being bored internally at suitable intervals, or blocked off by a baffle-ring, so as to form a restricted 45 discharge passage insuring supply of steam or water to the interior of the vulcanizer from all sides.

Embodiments of the invention are illustrated in the drawings in which:

50 Fig. 1 is a side elevation, largely in vertical section, of a preferred construction of the vulcanizer.

Fig. 2 is a horizontal section of the same through the header, part of a shell capping ring being shown in place,

Fig. 3 is a vertical section on the line 3—3 Fig. 2, showing an outside cover drain, and

Fig. 4 shows in vertical section a modified construction.

In the drawings I have illustrated the invention, as applied to a French press, a type of vulcanizer used exclusively for the curing of pneumatic casings. It consists of an upright steel shell or body portion 1, 65 usually sunk beneath a floor 2 so as to bring its mouth at a convenient elevation for introducing and removing a plurality of molds 3. At the top of the shell 1, a ring 4 is permanently secured, this being usually 70 cast with L-shaped slots 5 on its upper inner periphery for the reception of locking-lugs 6 on a cover 7 having crossing ribs 8 between which and a hydraulically operable platen 9, a plurality of molds 3 are adapted 75 to be clamped during a heat. The foregoing refers to the usual or typical construction of a French press.

According to my invention, I provide a 80 header for allowing steam or water to be supplied to the vulcanizer all around its inner circumference, or from a large number of points on all sides. In the preferred form, this is accomplished by providing the ring 4 (which heretofore has had a smooth 85 cylindrical inner surface) with an inwardly open groove or channel 10, which may be made or formed in casting the ring, this groove or channel being substantially semi-circular in cross-section and partially 90 blocked off or closed by a baffle-ring 11, which is adapted to be supported in any suitable manner, as by being rested upon the top of the shell 1, and which may have secured to it a plurality of guides 12 for 95 axially aligning the curing molds 3. The groove or channel 10 through a port 13 is in communication with a supply line 14 with branches 15 and 16 leading respectively to valve controlled steam and water 100 sources of supply. Adjacent the port 13, and for any extent necessary, preferably as shown in Fig. 2, the baffle-ring 11 may have secured to it an arcuate angle 17 for nearly closing the gap between the baffle-ring 11 105 and the contiguous portion of the cover 7 (or ring 4), thereby especially restricting the flow of fluid into the interior of the press in the region of the supply-port 13, and insuring circulation of the fluid around 110

the annular channel 10 for distributive flow over the baffle-ring into the heater. More complete closure may be effected by bending the angle 17 upwardly.

5 Condensation on the outside of the cover 7 may be drained off through a hole 18 and piping 19. For indicating temperatures and automatically controlling steam, tapped openings 20 may be provided for connection 10 of suitable appliances. For exhausting steam or water, an exhaust line (not shown) is provided, the connection being made where convenient and suited to the particular facilities for disposing of the waste 15 water, usually low down.

The invention is not limited to the precise details set forth in connection with the preferred construction illustrated in Figs. 1, 2 and 3, as the idea of providing a header 20 for flowing the steam or water into the vulcanizer from all sides, in order to minimize pipe connections, may be realized in a variety of forms and constructions, such, for instance, as shown in Fig. 4. In this 25 last mentioned figure, the header is formed by a completely closed annular conduit 21 cored in the shell-ring 4 and placed in communication with the interior of the press by any suitable number of openings 22. Of course, additional supply lines 14 could be 30 employed if desired and with some advantage over what has been used heretofore. For an understanding of the scope of the invention, reference is therefore made to 35 the annexed claims.

Having thus described my invention, what I claim and desire to protect by Letters Patent is:

1. A vulcanizing apparatus having a body 40 portion for receiving a plurality of molds, and a cover portion adapted to be secured to said body portion, one of said portions being provided with an annular channel in restricted communication with the interior 45 of the apparatus, and said annular channel being adapted to be supplied with fluid whereby steam or water may be distributively supplied to the interior of the apparatus through a single pipe.

2. A vulcanizing press consisting of a 50 shell, a ring secured to the shell at one end thereof, a cover adapted to be secured to the ring, and a platen operable within the shell for clamping a plurality of molds against the secured cover, said ring being 55 provided with an annular passage in restricted communication with the interior of the press at a plurality of points about its inner circumference, and a conduit for supplying fluid to said annular passage for 60 distributive introduction into the press from all sides.

3. A vulcanizing press having an upright shell, an annular ring fixed to the upper end of said shell, a cover detachably securable 65 to said ring, a platen operable within the shell for clamping a plurality of molds between itself and the cover, said ring being provided with an annular channel, and a baffle-ring largely closing the annular channel and defining with an adjacent portion of the cover a header whereby to insure steam or water supplied to the header flowing into the interior of the press from all sides.

4. A vulcanizing press having an upright 75 shell, an annular ring fixed to the upper end of said shell, a cover detachably securable to said ring, a platen operable within the shell for clamping a plurality of molds between itself and the cover, said ring being 80 provided with an annular channel, and a port in communication with said channel, a baffle-ring restricting communication between the annular channel and the interior of the press, and means on the baffle-ring 85 adjacent the port for insuring circulation of fluid around the annular channel.

5. A mold treating vulcanizer having a single admission port, and a header in communication with said port and of a girth 90 greater than the molds to be treated for permitting fluid supplied through said port thereto to be introduced into the interior of the heater from all sides.

Signed at Detroit, county of Wayne, 95 State of Michigan, this 21st day of February, 1922.

ROBERT N. VAN BUSKIRK.
